UNITED STATES PATENT OFFICE

2,638,834

PROPORTIONAL, CONVECTION WARMING
AND CIRCULATING SYSTEM

Ben Cones, Indianapolis, Ind.

Application February 8, 1950, Serial No. 143,018

2 Claims. (Cl. 98—33)

1

This invention relates to a system for introducing warm air into a room, such as in a class room of a school, and also withdrawing a certain proportion of the air which has been circulated through the room. The invention contemplates pressurizing to a slight extent the room. It has been determined that a desirable relationship between the air introduced, and the air withdrawn from the room, would be on the order of one-third new or fresh warm air coming into the room; one-third of the room air withdrawn under the pressure of that introduced air; and a recirculation of the remaining two-thirds room air with the incoming warm air.

This application is a continuation in part of my application filed in the United States Patent Office June 12, 1948, Serial Number 32,714, now abandoned, entitled Split Heating and Ventilating System.

A primary advantage of the present invention is to secure a better control of the proportioning of the incoming and outgoing air as well as the recirculation of the air within the room, and at the same time permit the use of a less number of air conducting ducts or flues.

In the present invention, a primary factor which makes the saving possible and a better over-all performance lies in the fact that the air to be recirculated and also the air to be taken out of the room and discharged into the atmosphere is in each instance taken through a common outlet opening. Heretofore it has always been considered necessary to employ two separate openings, one for the recirculating air, and one for the air being discharged from the room.

Other objects and advantages of the invention will become apparent to those versed in the art in the following description of the invention as illustrated diagrammatically in the accompanying drawings, wherein

Fig. 1 is a view in elevation of a fragmentary portion of a wall of a room to which the invention is applied;

Fig. 2 is a view in vertical section on the line 2—2 in Fig. 1; and

Fig. 3 is a vertical section through a structure embodying the invention as applied to a two story building.

Referring first to Figures 1 and 2 of the drawings, there are provided two vertically disposed air ducts 10 and 11, preferably adjacent one another. For the sake of identification, the duct or flue 10 will be termed the vent flue and the duct 11 will be termed the recirculating flue.

The vent flue 10 will vertically traverse the

entire height of the room 12, preferably behind one side wall 13. The vent flue 10 would be carried up in the usual manner to discharge preferably into the atmosphere. The recirculating flue 11 is provided with an entrance opening 14 at the floor level. An exit opening 15 is provided to have its lower margin at least eight feet above the floor level. The floor in this instance is designated by the numeral 16.

10 For an average class room having a space computed on the general average of two hundred and twenty-five cubic feet air space to each pupil, and there being approximately thirty to thirty-five pupils in the room, the vent flue 10 would be

15 preferably of a cross-sectional size of eight inches by eighteen inches. The eighteen inch dimension would be perpendicular to the wall 13. The recirculating flue 11 would have a cross-sectional area of twenty-four inches by twenty-four inches.

20 The lower opening 14 would be twenty-four inches by twenty-four inches. The upper opening 15 would have the dimensions of twenty-four inches by eighteen inches in height. The recirculating flue 11 will be closed off by a barrier 17 immediately above the top margin of the

25 opening 15.

It is to be noted that there is no direct opening from the room through the wall 13 into the vent duct 10. To the contrary, the vent 10 has an opening 18, herein shown as entirely thereacross from the wall 13 back to the opposite side of the duct 10, adjacent the floor 16, opening therein from the recirculating duct 11. In order to vary the effective area of this opening 18, a

30 damper 19 is mounted thereacross and is preferably externally operated by any suitable means such as by damper handle 20. It is intended that once the desired effective area is determined through the opening 18, that the damper 19 will remain fixed in the position for that effective area.

35 In other words, there is no need for further adjustment, and there is no automatic opening nor closing of this damper 19. It remains fixed after the initial adjustment.

40 A warm air duct 21, herein shown as tubular in nature, is entered into the recirculating duct 11 by coming substantially centrally thereof up through the floor 16 within the recirculating duct 11, and terminating by an end located for example, substantially thirty inches above the floor 16, and at least above the upper marginal edge 22 of the opening 14. The warm air duct 21 is

45 also preferably fitted with an injecting and diffusing jet head 53, the particular construction 50 of which does not enter into this invention per se.

For a detailed construction of this jet head 53, reference is made to my U. S. Letters Patent No. 2,543,152, granted February 27, 1951.

The operation of the structure in reference to the one particular set of conditions above indicated, is to carry air, previously warmed to the temperatures required, through the duct 21 and into the recirculating duct 11. The rate of flow of the air coming from the warm air duct 21 after it leaves the jet 53 to induce a flow of air from the room into the opening 14 and into the recirculating duct 11 is preferably around three-hundred cubic feet per hour. With this rate of flow of air into the recirculating duct 11, air will be discharged from the upper opening 15 at a rate of around four hundred feet per hour. This increase in volume is obtained by the inflow of air through the warm air duct 21.

This inflow of air from the duct 21 tends to pressurize the room. There may be set up a slight degree of vacuum at the opening 18 at the lower end of the vent duct 10 by reason of the difference in volume or weight of the air within the room 12 and the air externally thereof, or perhaps this slight degree of vacuum may be produced in the usual way by a revolving head ventilator on the upper end of the vent duct 10 (not shown). Be that as it may, the pressure set up in the room, will cause the air to enter through the opening 14 at a slight pressure, and this pressurized air may in part escape laterally from the recirculating duct 11 through that opening 18 to escape through the vent duct 10.

Thus it is to be seen, that a portion of the air flowing through the opening 14 will be diverted to be removed entirely from reentrance into the room by escaping through the vent duct 10. The other portion of that air will be pulled on up through the recirculating flue 11 to become warmed again from the warm air coming from the duct 21 and intermingled therewith to be returned to the room again through the opening 15.

As long as there is air pushed into the room through the duct 21, that system of partially withdrawing the air and recirculating the balance, at the same time fresh air is being introduced, will prevail.

The foregoing description has been made in reference to a structure primarily for a one story building. Reference is made to Fig. 3, wherein the structure is modified somewhat to apply to at least a two story building. In this form illustrated in Fig. 3, there are two side by side ducts 23 and 24 passing vertically upwardly through or along one side of the room 25 from the floor 26 thereof, through the ceiling 27, and through the next above room 28, and on up to at least the ceiling 29 of that room 28.

The duct 23 in its major portion between the floor 26 and the ceiling 27 serves as the recirculating flue or duct for the room 25. The warm air pipe 21 is entered centrally of and to extend into the duct 23 to terminate above the top edge 30 of the floor opening 31. Then spaced upwardly from the floor 26, for some distance such as about eight feet, there is the outlet opening 32 from which the air pulled in through the opening 31 may escape back into the room under the influence of the air being introduced through the warm air duct 21. The duct 23 is closed off immediately above the opening 32 by the barrier 33. As is indicated in the drawing Fig. 3, this barrier 33 is spaced a distance below the ceiling 27.

A vent opening 34 is provided inside of the duct 23 adjacent the floor 26 within the zone where air is coming into the duct 23 from the opening 31. This opening 34 has its effective area controlled by a damper 19.

The duct 24 between the floor 26 and the ceiling 27 serves as a vent flue or duct. This duct 24 is closed by a barrier 35 at the floor level 26, and is further closed substantially at the level of the ceiling 27 by the barrier 36. A vent opening 37 is provided between the duct 24 below the barrier 36 into the duct 23 above the barrier 33. The duct 23 is open at its upper end to some air receiving space, preferably the atmosphere.

A warm air duct 38 is carried centrally upwardly through the duct 24, through the barrier 35, and the barrier 36, to terminate in an upper portion of the duct 24 above the top edge 39 of the opening 40 from the upper room 28. Spaced upwardly from this opening 40, such as eight feet above the ceiling 27 or the consequent floor level of the room 28, is a discharge opening 41, whereby air in the duct 24 may escape through that opening 41 into the room 28 after being heated by air discharging from the warm air duct 38. At the upper marginal edge 42 of the opening 41, there is fixed a barrier 43 across the duct 24. A vent opening 44 is provided in the side of the duct 23 adjacent the level of the barrier 36, and within the duct 24 to permit air pressurized in the room 28 to escape partially through that opening 44, while the other part of the air will be carried on up the duct 24. A damper 19 controls the effective opening of this vent opening 44.

The air to be taken from the room 25, which is a portion of the air entering the duct 23 through the opening 31, escapes through the opening 34 into the duct 24, to travel upwardly therein and leave that duct 24 through the opening 37 to enter the duct 23, and escape from the upper end thereof. Also the air to be taken from the room 28 comes through the duct opening 40 and leaves that duct through the opening 44 to enter the upper portion of the duct 23 and thus escape from its upper end.

As indicated in Fig. 3, where the duct 23 may be located to be adjacent a cloakroom 46, a discharge from that cloakroom may be had through a narrow opening 47 from the room into the upper portion of the duct 23 above the barrier 33. Since the room 25 is pressurized, some air will tend to escape around the cracks of the door 48 if it be closed, or through the door opening if it is allowed to remain open, and thus air may be circulated through that room 46 to escape through the opening 47.

In respect to the barriers 17, 33, and 43, each of these barriers is illustrated in the drawings as being flat and horizontally disposed members, that is from their undersides, to be in a plane including approximately the top marginal edge of the respective openings 15, 32, and 42. This construction provides a plenum chamber in each instance, with the barrier as the top chamber wall and with a side opening into the room, the purpose being to transform the kinetic energy of the upwardly flowing air into pressure energy.

It is therefore to be seen that I have provided a very simple, yet a most effective means for accomplishing the above indicated results. It is obvious that structural changes may be employed to differ from the constructions specifically set forth, and I therefore do not desire to

be limited to that precise construction beyond the limitations of the following claims.

I claim:

1. In a system for introducing fresh air into and proportionally changing the air content of a room, the combination of a recirculating air flue and a vent flue extending side by side vertically of the room; means for inducing an up air flow in said vent duct; said recirculating flue having a fixed sized, intake opening therein from the room at the room floor level and a fixed sized discharge opening therefrom near the ceiling of the room, the recirculating flue being otherwise closed off at said room floor and ceiling; said vent flue having a sole intake opening 10 therein from said recirculating flue at said floor level; a fresh air duct conveying air under pressure and carried upwardly from the floor level to open into said recirculating flue above its said floor level opening and above said vent flue floor level opening.

2. In a system for introducing fresh air into and proportionally changing the air content of a room, the combination of a recirculating air flue and a vent flue extending side by side vertically of the room; means for inducing an up air flow in said vent duct; said recirculating flue having a fixed sized, intake opening therein from the room at the room floor level and a fixed sized discharge opening therefrom near the ceiling of 25

the room, the recirculating flue being otherwise closed off at said room floor and ceiling; said vent flue having a sole intake opening therein from said recirculating flue at said floor level; a fresh air duct conveying air under pressure and carried upwardly from the floor level to open into said recirculating flue above its said floor level opening and above said vent flue floor level opening; and damper means in said vent flue opening confining that opening to be at all times less than said recirculating flue floor level opening, whereby the room air induced to flow from the room by said recirculating flue under ejector action induced by said fresh air duct discharge is divided through a differential in pressure as between said two floor level openings to have a proportion of that room air divided and separated for vent flue discharge prior to mixing of the room air in any part thereof with air from said fresh air flue.

BEN CONES.
